(57) **CLAIM**

The ornamental design for a thermal pad, as shown and described.

DESCRIPTION

FIG. 1 is a front view of a thermal pad of the present invention. FIG. 2 is a rear view of the thermal pad of FIG. 1. FIG. 3 is a top plan view of the thermal pad of FIG. 1. FIG. 4 is a bottom view of the thermal pad of FIG. 1. FIG. 5 is a right side view of the thermal pad of FIG. 1. FIG. 6 is a left side view of the thermal pad of FIG. 1. FIG. 7 is an end view taken along the line 7-7 of the thermal pad of FIG. 1. FIG. 8 is an enlarged view taken along the line 8-8 of the thermal pad of FIG. 7. FIG. 9 is an enlarged view taken along the line 9-9 of the thermal pad of FIG. 7; and, FIG. 10 is a rear view of the thermal pad of FIG. 1 from which the release sheet has been removed for clarity of disclosure, it being understood that the stippled areas indicate adhesive surfaces. The broken lines in the drawings represent claimed perforations on the thermal pad.
